UNITED STATES PATENT OFFICE.

THOMAS C. WHITEHEAD, OF DETROIT, MICHIGAN.

FLOAT CHAMBER.

Application filed January 7, 1924. Serial No. 684,861.

This invention relates to refrigerating apparatus and refers more particularly to the float chambers thereof.

An object of the invention is to provide 5 a float chamber having a closure that is provided with passages through which the refrigerating medium may be supplied to and removed from the chamber and that is also provided with means for supporting 10 the valve controlling the flow of the medium through one of the passages as well as the pivot for the float arm that actuates the valve whereby these parts may be applied to or removed from the chamber as a unit.

Another object is to provide a simple and compact construction that may be manufactured at a comparatively low cost.

With the above and other objects in view the invention consists in certain novel features of construction, combinations and arrangements of parts as will be more fully described and particularly pointed out in the appended claim.

In the accompanying drawing: 25 Figure 1 is a vertical sectional view through a float chamber embodying my invention;

Figure 2 is an end view thereof. 30 Referring now to the drawing in which like characters of reference designate corresponding parts throughout the several views the numeral 1 designates a float chamber preferably having laterally extending feet 2 that are adapted to be attached to a suitable support such as the top of a brine tank (not shown) of a refrigerating apparatus.

The float chamber may be any shape desired and may be constructed of any suitable material, the chamber shown in the drawing being preferably an elongated casting having a closed end 3. The open end of the chamber is preferably closed by a cap 4 that is detachably secured to the chamber. This cap is also preferably a casting and has inlet and outlet passages 5 and 6 respectively through which the refrigerating medium may be supplied to and removed from the chamber when the cap is attached thereto. The outlet passage 6 is preferably formed in an inwardly projecting enlargement 7 of the cap and is provided with the spaced longitudinally extending

portions 8 and 9 respectively and a vertical portion 10 connecting the adjacent ends of 55 the portions 8 and 9. The portion 9 is preferably larger in diameter than the portion 8 and is adapted to be connected to a suitable conduit (not shown) for conveying the refrigerating medium to the usual expansion coils within the brine tank, while the portion 10 is relatively small in diameter and is preferably provided with a conical seat portion 11 at the upper end thereof for receiving the tapered end of a valve 12. 60 This valve has an enlarged stem portion 13 that is slidably mounted in aligned vertical openings 14 and 15 respectively formed in the enlargement 7 and in a horizontal projection 16 extending inwardly from the cap 70 4 immediately below the inlet opening 5.

For operating the valve 12, I preferably provide a float 17 having a relatively long arm 18 that is preferably pivoted on a lug 19 projecting inwardly from the cap 4 intermediate the projection 16 and enlargement 7 and that is connected to the stem 13 of the valve by a pin 20. This pin preferably extends through the stem and loosely engages aligned elongated openings 21 in 80 the bifurcated end portion of the arm 18. Thus, the valve 12 will be operated by the arm 18 of the float and the movement of the latter will be controlled by the level of the refrigerating medium in the chamber. 85

From the foregoing description it will be apparent that all of the desired results are obtained by the use of relatively few parts and that in view of the simplicity of construction the cost of manufacturing the chamber has been reduced to a minimum. Furthermore, repairs may be easily and quickly made when required by simply removing the cap which carries all of the working parts. 90

What I claim as my invention is:

A float chamber for a refrigerating apparatus comprising a casing having an opening at one end thereof, of a cap for said opening having an inlet passage at the upper end thereof through which the refrigerant may be supplied to the chamber and having an inwardly extending enlargement, said enlargement having spaced longitudinally extending passages respectively opening 100 105 interiorly and exteriorly of said chamber.

2
ber and a transversely extending passage connecting said longitudinally extending passages, an inwardly extending projection above the enlargement, a valve pin slidably mounted in the projection and enlargement for controlling the flow of fluid through the transversely extending passage, and means for controlling the movement of said valve pin including an arm pivoted upon the cap intermediate the projection and enlargement and pivotally connected to the valve pin, and a float carried by said arm.

In testimony whereof I affix my signature.
THOMAS C. WHITEHEAD.
